COUNTER UNIT

George McElveen Wynn, Atlanta, Ga., assignor to
The Auto-Soler Company, a corporation of
Georgia

Application February 18, 1949, Serial No. 930

Term of patent 14 years

(Cl. D9—2)

To all whom it may concern:

Be it known that I, George McElveen Wynn, a citizen of the United States, residing at Atlanta, in the county of Fulton and State of Georgia, have invented a new, original, and ornamental Design for a Counter Unit, of which the following is a specification, reference being had to the accompanying drawing forming part thereof, and in which the single figure is a perspective view of a counter unit, showing my new design. The side of the counter unit which is not shown in the drawing corresponds exactly with the side which is shown, and the back of the counter unit not shown is substantially plain.

I claim:

The ornamental design for a counter unit, substantially as shown and described.

GEORGE McELVEEN WYNN,
